UNITED STATES PATENT OFFICE.

MORTHEN J. THUESTAD, OF SAN FRANCISCO, CALIFORNIA, ASSIGNOR TO
ENDRE MATIAS LIND, OF SAME PLACE.

DOOR-CATCH.

SPECIFICATION forming part of Letters Patent No. 643,612, dated February 13, 1900.

Application filed August 16, 1899. Serial No. 727,441. (No model.)

To all whom it may concern:

Be it known that I, MORTHEN J. THUESTAD, a citizen of Norway, residing at San Francisco, in the county of San Francisco and State of California, have invented certain new and useful Improvements in Door-Catches, of which the following is a specification.

My invention relates to an improved door-
10 catch, the object of my invention being to
provide a device of this character which will
be especially suited for the doors of steamers
or other vessels, and in particular to provide
a door-catch in which the door-hook shall be
15 shielded when not in use, so as to avoid in-
jury from the sharp point thereof coming in
contact with persons passing near the door,
and one which will prevent rattling of the
door when so held by said catch.

20 My invention therefore resides in the novel
construction, combination, and arrangement
of parts for the above ends hereinafter fully
specified, and particularly pointed out in the
claim.

25 In the accompanying drawings, Figure 1 is
a top view of my improved catch, the door
and wall being shown in broken-away section.
Fig. 2 is a side elevation of the device in
operation. Fig. 3 is a horizontal section there-
30 of. Fig. 4 is a vertical section. Fig. 5 is an
end view. Fig. 6 is a side elevation of the
catch proper, and Fig. 7 is a vertical section
thereof.

I represent my improved catch secured to a
35 door 2 by means of screws 3 through the
circular flange 4 at the base of the catch. From
said flange extends horizontally outward a
short tube 5, and in said tube is contained a
hook whose shank 6 has a pivot-hole alined
40 with two holes 7 in opposite sides of the tube
5, and through said holes passes a pivot-bolt 8.
Thus said shank rocks vertically on said pivot.
The shank 6 has a forked tail 9, which is en-
gaged by a pin 10, said pin being cut out on
45 each side a short distance above its lower end,
leaving a web 11 passing through said fork,
so that a vertical movement of the pin in
either direction rocks the hook on its pivot.
Said pin extends upward through a hole in
50 the tube 5 and carries on its upper end a suit-

able head 12, and between said head and the
outer surface of the tube 5 is interposed a
compressed spiral spring 22. Said spring nor-
mally raises the tail of the shank 6, and there-
fore normally depresses the hook 13 of said 55
shank. Coöperating with said hook is a loop
14, formed by a U-shaped piece of metal se-
cured by screws 15 to the wall 16, against
which the door is to be held open, and when
the door is swung open the inclined front face 60
17 of said hook engages the front of said loop
and is raised thereby against the pressure of
the spring 22 until the hook passes over said
loop and is held thereby. Pressure upon the
head 12 of the pin 10 will raise the hook and 65
free the catch.

When the door is closed, the hook is not in
use, and in order to prevent injury to per-
sons or clothing from the point of the hook
in this position there is provided a cylindrical 70
sleeve 18, sliding upon the tube 5 and hav-
ing its outer end 19 closed except for a verti-
cally-elongated slot 20, through which the
hook 13 passes. A compressed spiral spring
21, interposed between the outer end of the 75
tube 5 and the inner surface of the end 19 of the
sleeve, serves to normally extend the sleeve
from the tube, and the sleeve is sufficiently
extended normally to completely shield the
hook 13 and prevent injury therefrom. Slots 80
23, cut in the sides of the sleeve and through
which the pivot-bolt 8 passes, limit this
movement of the sleeve. When the door is
swung wide open, the loop 14 first engages
85 the end 19 of the sleeve and pushes it inward
on the tube 5, thereby exposing the point of
the hook 13, and the continued movement of
the door raises said hook and causes it to en-
gage the loop in the manner already explained.

The sleeve 18 and spring 21 perform two 90
useful offices or functions—first, they prevent
rattling of the hook and loop against each
other, and, secondly, they shield the front of
the hook when not in use and prevent acci-
dental injury or damage therefrom. 95

I claim—

The combination of a catch on a door com-
prising a tube 5, a hook having a horizontal
pivot in said tube, and having a tail, a spring-
actuated vertically-reciprocating pin engag- 100

ing said tail, a cylindrical sleeve sliding upon the tube, closed at its outer end except for a vertical slot through which the hook passes, a compressed spiral spring, surrounding the 5 shank of the hook, interposed between the end of the tube and the inner surface of the end of the sleeve, said sleeve being slotted as at 23, and the pivot-bolt of the hook passing through said slots to limit the movement of 10 the sleeve, and a horizontal U-shaped loop

on the opposite wall which said hook engages, substantially as described.

In witness whereof I have hereunto set my hand in the presence of two subscribing witnesses.

M. J. THUESTAD.
